(57) **CLAIM**

The ornamental design for protective headgear for use with hooded dryers, as shown and described.

DESCRIPTION

FIG. 1 is a front elevational view of a protective headgear for the use with hooded dryers showing my new design;

FIG. 2 is a rear elevational view thereof;

FIG. 3 is a side elevational view thereof;

FIG. 4 is a top plan view thereof;

FIG. 5 is a bottom plan view thereof;

FIG. 6 is a top front perspective view ; and,

FIG. 7 is a perspective view shown in use.

The broken lines shown in FIG. 7 are for illustrative purposes only and form no part of the Applicant's claimed invention.

1 Claim, 4 Drawing Sheets

FIG. 1

FIG. 2

FIG. 3

FIG. 5

FIG. 4
